J. A. FREMON

PIN TUMBLER LOCK

Filed Dec. 8, 1921

Inventor
Jules A. Fremon.
By G. P. Cornwell, Mfg.

UNITED STATES PATENT OFFICE.

JULES A. FREMON, OF LEEPER, MISSOURI.

PIN-TUMBLER LOCK.

Application filed December 8, 1921. Serial No. 520,949.

To all whom it may concern:

Be it known that I, JULES A. FREMON, a citizen of the United States, residing at Leeper, county of Wayne, State of Missouri, have invented a certain new and useful Improvement in Pin-Tumbler Locks, of which the following is a full, clear, and exact description, such as will enable others skilled in the art to which it appertains to make and use the same, reference being had to the accompanying drawings, forming part of this application.

My invention relates to pin tumbler locks of the type disclosed in my copending applications Serial Numbers 510,830 and 514,245, and consists in a construction of such locks which adapts them for operation by a series of keys, all of which must be used in the proper order to operate the lock.

The main object of my invention is to provide a pin tumbler lock, each tumbler of which may consist of a plurality of segments adapted to be consecutively raised to different heights by different keys to part at different points, and thereby permit successive rotation of respective portions of the lock which are normally held in locked position by engagement therewith by the pin tumblers.

An additional object of my invention is to provide a changeable key construction for such a lock wherein any one of the multiple keys used in the lock's operation may be changed by the possessor thereof, so that the original key cannot be successfully used and so that other keys of the series required for the lock's operation will not be affected.

A further object of my invention is to provide an adjustable feature whereby the lock may be set to be operated completely by any desired one of the series of keys fitted thereto.

In the accompanying drawings, which illustrate my invention,—

Figure 1 is a vertical longitudinal section through my improved lock with one of the multiple keys inserted.

Figures 2 to 6 inclusive are vertical transverse sections taken on the line 2-2 of Fig.

ure 1, but showing the elements of the lock in different operating positions, as herein-after described.

Figures 7 and 8 are details of two of the lock members.

Figures 9 and 10 are sections similar to Figures 2 to 6, but illustrating a modification of my lock which renders the keys changeable.

The lock case 1 is cylindrical with upper and lower rectangular projections 2 and 3, respectively. Rotatable within case 1 is an annular ring 4. Rotatable within ring 4 is an annular ring 5 and rotatable within ring 5 is a cylindrical plug 6. The rear end of ring 4 projects slightly beyond the rear of case 1. The rear end of ring 5 projects slightly beyond the end of ring 4 and the rear end of plug 6 projects slightly beyond the rear of ring 5. These projecting ends of the two rings and the plug carry respective cams 7, 8 and 9, either of which is adapted to engage an adjustable collar 10 on the latch bolt 11 when the collar is aligned therewith.

Referring now to Figure 2, it will be seen that ring 5 is provided with two uniting pins 12 and 13. The point of pin 12 projects into a recess 14 in ring 4, thus temporarily locking rings 4 and 5 against relative rotation. The head of pin 13 projects into a recess 15 in ring 4, thus temporarily withdrawing the point of the pin within the inner periphery of the ring so that it does not interfere with rotation of plug 6.

Ring 4 is similarly provided with pins 16 and 17 and case 1 with a recess 18 for the point of pin 16 and a recess 19 for the head of pin 17. Each of the above-mentioned pins is preferably provided with a coil spring tending to thrust the pin in the direction which its head faces. (See Figs. 7 and 8). Thus pins 12 and 16 tend to move inwardly and pins 13 and 17 tend to move outwardly.

Each of the recesses for the heads of pins 12, 13, 16 and 17 has one edge inclined as shown which serves to cam the pin out of the recess upon such relative rotation of the

two members, with which the head engages, as will force the inclined edge against the pin head. Plug 6 and ring 5 are provided with recesses 20 and 21, respectively, adapted to receive the points of pins 13 and 17, respectively, when aligned therewith.

Plug 6, ring 4 and ring 5 are provided with studs 30, 31 and 32, respectively, and ring 4, ring 5 and case 1 are provided with respective slots 33, 34 and 35 extending substantially half-way around the respective inner peripheries of the rings and case and serving with studs 30, 31 and 32 to permanently limit the relative rotation of the adjacent members which carry them.

Projections 2 and 3 in case 1 are each provided with a series of recesses for driver pins 22. I have shown five of such recesses in each projection, but this number is immaterial and as the drivers in each recess are manipulated in the same manner, the description hereafter will refer only to the two drivers on line 2-2.

Rings 4 and 5 and plug 6 are provided with a series of transverse pin-ways extending in straight lines through these members and adapted to be aligned, respectively, with the recesses in projections 2 and 3 on case 1. These pin-ways in the rings and plug are filled with pin tumbler segments adapted to be thrust outwardly by the bits of a key A when the same is inserted in the lock and to be thrust inwardly by springs 23 and 24 which press on the case drivers. The key A is held against movement transversely of the plug by the usual rib A' and a corresponding recess in the plug.

Assume key A to be the first of the series of multiple keys which operate the lock and inserted in plug 6. The two (or more) pin tumbler segments 25 and 26 in plug 6 are raised so that their outer ends are flush with the outer periphery of plug 6. Rotation of key A to the right as far as possible will move the plug to the position shown in Figure 3 which will align recess 20 with the point of pin 13 and will align a recess 27 with the head of pin 12. The spring on pin 12 will immediately thrust the pin inwardly so that its head enters recess 27 in plug 6 and disengages ring 4, thus ceasing to function to prevent relative rotation of the two rings.

Key A is now withdrawn and the next key B of the series may be inserted, as shown in Figure 4, whereby the outer end of tumbler segments 25 and 28 are raised to the outer periphery of ring 5. Righthand rotation of key B will now cam pin 13 inwardly out of the recess in ring 4 and into recess 20 in plug 6 and rotate the plug and ring 4 as a unit to the position shown in Figure 5.

The third key C is now inserted (Figure 6) and raises the pin tumblers so that the

outer end of tumbler segments 28 and 29 are raised flush with the outer periphery of ring 4 which leaves ring 4 free to rotate in case 1. Such rotation cams pin 17 into ring 4 thus locking the two rings together. As plug 6 and ring 5 have been previously united by inward movement of pin 13 it is obvious that the plug and both rings will rotate as a unit within the case to throw the lock bolt to unlocked position.

When the lock is to be locked it will be necessary to use each key in the reverse order in which they were used in the unlocking operation.

It is to be understood that the pin tumblers serve to hold the lock members against any movement except when certain keys are inserted and the function of the uniting pins is to prevent simultaneous movement of the plug and rings prior to the successive rotation of the members as described.

While I have shown two rings between the plug and the case, one could be used without changing the construction of the lock and only two keys would be required to operate the lock. Of course, the rings may be increased in number to any desired extent.

In Figures 9 and 10, I have illustrated a construction which requires two keys to be used in succession to operate the lock and either of these keys may be changed by the possessor thereof for another key having a different bit arrangement. In these figures, the case 40 and plug 41 are like case 1 and plug 6 above described, except that case 40 is provided with a longitudinal recess which receives a sliding bar 42, similar to that shown in my copending application, Serial Number 514,245, which normally provides a continuous portion of the interior periphery of the case upon which slides the head of uniting pin 43 in ring 44. Bar 42 may be retracted manually however, so as to align a recess therein with the path of movement of pin 43, which recess will receive the head of the pin and permit retraction of the point of the pin from ring 45 when key X is turned to the left.

Ring 45 may then be rotated further to the left until its stud 46 reaches the end of slot 47 in ring 44 when the ring pin-way will be aligned with a pin segment reservoir 48 in ring 44 and key X may be withdrawn and a different key inserted, the difference in the height of the bits being accommodated by a lesser or greater number of pin segments remaining in ring 44.

Plug 41, ring 49 and ring 45 are then turned to the right and when stud 46 reaches the righthand end of slot 47, it will positively engage ring 44 when the inclined edge of the bar recess in case 40 will cam pin 43 back into the normal position shown in Figure 9.

Ring 49 has a pin segment reservoir 54 and a slot 53 and ring 45 has a bar 55 corresponding to the similar elements 48, 47 and 42 in ring 44 and case 40. These parts 5 enable plug 41 with its stud 52 to be rotated to a key changing position in which the number of pin segments in the plug may be changed without changing the distance from the axis of the plug to the outer 10 end of the composite tumbler in plug 41 and ring 49 when the new key is in the lock.

When the lock is to be operated in the ordinary manner, the above described key-changing-elements do not function. Then, a stud 51 on ring 44 and a slot 55 in case 40 function as do stud 32 and slot 35 in the preferred form previously described. Similarly ring 49 and ring 45 are provided, respectively, with a stud 56 and a slot 57. When the first operating key has rotated plug 41 and ring 49 to the right as far as stud 30 and slot 34 permit, it is withdrawn and a second operating key inserted, which 25 raises the pin tumblers so that they may part at the outer periphery of ring 44 and permit further rotation of both rings and the plug to the limit provided by stud 51 in slot 50, which will unlock the lock. These 30 partial rotations by different keys must be reversed to return the lock to locked position.

In this modification, the lower pin-way in the plugs and rings is not continued into ring 44 and the lower pin tumblers cannot be positioned in the upper pin-way so as to render inoperative the key changing elements.

In this construction, the total rotation of the plug is limited to less than a full revolution by studs 51 and 52 and their slots but such limited rotation is ample to provide for the use of two multiple keys and their tumbler segment changing elements.

I contemplate the usual changes in the details of my device as will occur to those skilled in the art and other modifications of my invention as come within the scope of the following claims.

50 I claim:

1. In a multiple key lock, a case, a member rotatable therein, means definitely limiting the rotation of said member in said case, a plug rotatable in said member, means definitely limiting the rotation of said plug in said member, pin tumblers for locking said member to said case and for locking said plug to said member, and adapted to be actuated by a key to release said plug from said member and then to be actuated by a second key to release said member from said case, and a lock bolt operated by rotation of said member.

2. In a multiple key lock, a case, a member rotatable therein, an arcuate slot in said case,

a stud on said member extending into said slot, a plug rotatable in said member, an arcuate slot in said member, a stud on said plug extending into said member slot, pin tumblers normally preventing rotative movement of said member and plug but adapted to be key-actuated to prevent their so functioning for both case and member and plug and member simultaneously, and uniting pins respectively locking said case and member together and said plug and member together and adapted to disunite their respective elements upon rotation of the latter.

3. In a multiple key lock, a rotatable plug, a rotatable member surrounding the same and limiting its rotation, a second member surrounding said first-mentioned member and limiting its rotation, means for uniting said members and adapted to disunite the same when said plug is rotated to the limit provided by said rotatable member.

4. In a multiple key lock, a rotatable plug, a rotatable member surrounding the same and limiting its rotation, a second rotatable member surrounding said first-mentioned member and limiting its rotation, a case surrounding said second rotatable member and limiting its rotation, means for uniting said members, means for uniting said second member and said case, said means being adapted to disunite the respective parts mentioned when said plug is rotated to the limit provided by said first-mentioned rotatable member, and said plug and first-mentioned member are subsequently rotated to the limit provided by said case, respectively.

5. In a multiple key lock, a plurality of successively rotatable members, each rotated by the insertion of an individual key, a cam on each of said members, and a lock bolt adapted to be engaged by any predetermined one of said cams.

6. In a multiple key lock, a plurality of successively rotatable members, each rotated by the insertion of an individual key, a cam on each of said members, a lock bolt, and a shoe slidably on said bolt to be adjusted to engage any one of said cams.

7. In a lock, a plug member, an annular ring surrounding said plug, a member enclosing said ring, radial recesses in said plug and enclosing member, and a pin slidably mounted in said ring and adapted to enter either one of said recesses to unite said ring with said plug or to free said ring therefrom respectively.

8. In a lock, a plug member, an annular ring surrounding said plug, a member enclosing said ring, radial recesses in said plug and enclosing member, pins slidably mounted in said ring and adapted to enter said recesses in said plug member and enclosing member, respectively, to unite said ring to said plug member or to said enclosing member.

or to enter recesses in said enclosing member and plug member, respectively, to free said ring from said other members.

9. In a lock, a plug member, an annular ring surrounding said plug, a member enclosing said ring, radial recesses in said plug and enclosing member, pins slidably mounted in said ring and respectively adapted to extend alternately in opposite directions from the peripheries of said ring to unite the latter to one of said members or to free said ring from the other of said members.

10. In a lock, a plug member, an annular ring surrounding said plug, a member enclosing said ring, radial recesses in said plug and enclosing member, a pin slidably mounted in said ring and adapted to enter either one of said recesses to unite said ring with said plug or to free said ring therefrom, respectively, and means for thrusting said pin into one of said recesses when aligned therewith, and means for thrusting said pin into the other of said recesses when moved from such alignment.

11. In a lock, a plug member, an annular ring surrounding said plug, a member enclosing said ring, radial recesses in said plug and enclosing member, pins slidably mounted in said ring and adapted to enter said recesses in said plug member and enclosing member, respectively, to unite said ring to said plug member or to said enclosing member or to enter recesses in said enclosing member and plug member, respectively, to free said ring from said other members, means for thrusting one of said pins into a recess in said plug when aligned therewith, and means for thrusting the other of said pins out of a recess in said enclosing member upon subsequent rotation of the plug and said ring.

12. In a lock, a plug, an annular ring surrounding said plug, a member enclosing said ring, a pin slidably radially through said ring and longer than the thickness of the latter, and radial recesses in said plug and enclosing member adapted to receive opposite ends of said pin respectively when aligned therewith.

13. In a lock, a plug, an annular ring surrounding said plug, a member enclosing said ring, a pin slidably radially through said ring and longer than the thickness of the latter, radial recesses in said plug and enclosing member adapted to receive opposite ends of said pin respectively when aligned therewith, means for thrusting said pin into one of said recesses when aligned therewith, and means for withdrawing said pin from that recess when the ring is rotated relatively to that recess.

14. In a multiple key lock, a plug, a case, a plurality of radial pin-ways in said plug and case in the same transverse plane, pin tumbler segments in said pin-ways normally

locking said plug to said case and adapted to be raised in one of said pin-ways by one key to permit partial rotation of said plug and to be raised in the other of said pin-ways by another key to permit further rotation of said plug.

15. In a multiple key lock, a plug, a case, a plurality of radial pin-ways in said plug and case in the same transverse plane but extending in opposite directions, pin tumbler segments in said pin-ways normally locking said plug to said case and adapted to be raised in one of said pin-ways by one key to permit one-half a revolution of said plug and to be raised by another key in the other pin-way to permit further rotation of said plug.

16. In a multiple key lock, a case, a ring rotatable therein, a plug rotatable in said ring, pin tumblers locking said plug and ring against rotation in said case, said tumblers being adapted to be parted between said plug and ring by a key to permit rotation of said plug in said ring, means limiting such rotation, said tumblers being adapted to be parted between said ring and case by another key to permit further rotation of said plug with said ring.

17. In a changeable key pin tumbler lock, a case, a plug, annular members therebetween, a pin-way through said members, case and plug, a series of pin tumbler segments in said pin-way which adapt the pin tumblers formed thereby to be parted at various points in their length to permit different keys of a series to function in succession to complete operation of the lock, and means whereby one of said keys may be changed without affecting the movement of said pin tumblers when engaged by another key of said series.

18. In a pin tumbler lock, tumblers adapted to be repeatedly raised by successive keys used in a predetermined order to unlock the lock and adapted to be repeatedly raised by the same keys in reversed order to lock the lock.

19. In a pin tumbler lock, tumblers adapted to be raised by successive keys used in a predetermined order to unlock the lock, and means requiring the use of the same keys in the reverse order to lock the lock.

20. In a changeable key pin tumbler lock, a case, a plug, annular members therebetween, a pin-way through said members, case and plug, a series of pin tumbler segments in said pin-way which adapt the pin tumblers formed thereby to be parted at various points in their length to permit different keys of a series to function in succession to complete operation of the lock, and means whereby any one or more of said keys may be changed without affecting the movement of said pin tumblers when engaged by another key of said series.

21. In a pin tumbler lock, means whereby a plurality of keys must be used in succession to completely operate said lock, and means for changing one of said keys without affecting the operation of the other of said keys.

22. In a pin tumbler lock, a set of pin tumblers all of which are operable by each key of a series, which keys are used in suc-

cession to completely operate the lock, and means for changing the lengths of said tumblers so that any one key of the series may be changed without affecting the operation of the other key or keys of the series.

In testimony whereof I hereunto affix my signature this 1st day of December, 1921.

JULES A. FREMON.
